PNEUMATIC PICKOFF FOR TWO DEGREE OF FREEDOM GYRO

James V. Johnston, Huntsville, Ala., assignor to the United States of America as represented by the Secretary of the Army

Filed Feb. 3, 1965, Ser. No. 430,223
8 Claims. (Cl. 74—5.6)

The invention described herein may be manufactured and used by or for the Government for governmental purposes without the payment of any royalty thereon.

The invention relates to a two degree of freedom gyro with an all pneumatic system.

With the advent of fluid amplifiers and reaction control for missiles, an all pneumatic system is necessary including the inertial sensing device.

Therefore, it is an object of this invention to provide an all pneumatic system for a gyro.

Another object of this invention is to provide a gyro that allows for high *g* acceleration.

Still another object of this invention is to provide an extremely simple pneumatic gyro.

Yet another object of this invention is to provide a pneumatic gyro that can be fabricated from cheap component parts.

In accordance with this invention, a new pneumatic gyro system is provided that includes a stationary spherical stator member about which a rotor member is rotatably mounted by means including air bearing means. The rotor member has a reaction ramp surface against which fluid, from different positions around the stator member, is directed to generate signals. Said signals are then utilized to control fluid amplifier means, and the outputs from the fluid amplifier means can be used to control devices desired in one or two degrees of freedom such as control surfaces of a missile.

In the accompanying drawing forming a part of this specification, and in which like numerals are employed to designate corresponding parts throughout the same:

FIGURE 1 is a view, partially in section, of a gyro in accordance with this invention and illustrating the fluid amplifier means schematically,

FIGURE 2 is a sectional view taken on line 2—2 of FIGURE 1, and

FIGURE 3 is a view, partially in section, and taken on line 3—3 of FIGURE 1.

The invention may be better understood by referring to the drawing wherein, numeral 1 designates a casing that supports stator member 3 by being secured thereto in a conventional manner. Stator member 3 has a spherical ball portion 5 about which a free rotor member 7 surrounds the stator in an equatorial plane. Spherical ball portion 5 and rotor member 7 are separated by an air gap 9. Rotor member 7 is supported through the use of air from a high pressure source 11 that is communicated through passage 12 to channels 13 in stator member 3 and into air gap 9. Exhausting of this air into air gap 9 creates pressure which floats rotor member 7. Channels 13 open into the air gap so as to surround the spherical ball portion 5 and create a latitude band of support holds on each end.

Rotor member 7 may be rotated by conventional means such as by turbine means of the type disclosed in U.S. Patent No. 2,086,896.

A pneumatic pickoff control for the gyro includes four control positions or orifices 15, 17, 19, 21 (see FIGURE 2), located 90° apart around the periphery of spherical portion 5. Air or other gas is delivered from a high pressure supply means 23 to a manifold 25 and to each of the four control positions by way of fluid passages 27. Each fluid passage 27 has an orifice or

2

throttle 29 near manifold 25 and an orifice or throttle 31 near the control position to define a chamber 33 between orifices 29 and 31. Each chamber 33 communicates with a pickoff control passage 35 that has an orifice 37 mounted therein. Pickoff control passages 35, for control positions 15 and 19, are connected as opposing controls for a first conventional type fluid amplifier 39, such as the push-pull type. Pickoff control passages 35 for control positions 17 and 21 are connected as opposing controls for a second conventional type fluid amplifier 41. The outputs 40 and 42 from amplifiers 39 and 41 can be used to actuate control means as desired to control in one or two degrees of freedom.

The control fluid supplied to control positions 15, 17, 19, 21 is directed toward an inner circumferentially tapered ramp surface 43 on rotor 7 and exhausted through slots 45 in rotor 7 and exhaust opening 47 in casing 1 (see FIG. 1).

In operation, air from source 11 is supplied to air gap 9 to support rotor 7, and rotor 7 is rotated in a conventional manner by fluid turbine means. With the rotor rotating, air pressure from high pressure supply means 23 is utilized to provide an air pressure p_1 in manifold 25. Air is then communicated from manifold 25 to chambers 33 across orifices 29 to establish p_2 pressures in chambers 33. Air is next communicated from chambers 33 across orifices 31 to control positions 15, 17, 19, 21. So long as the distances between the control positions and tapered ramp surface 43 remain equal, the p_2 pressures in chambers 33 will be equal. However, for example, if rotor member 7 is pivoted to the right as viewed at the top of FIGURE 1, the distance between control position 15 and the portion of tapered ramp surface 43 immediately above control position 51 will be greater than the distance between control position 19 and the portion of tapered ramp surface 43 immediately below control position 19 to thereby cause the p_2 pressure in chamber 33 for control position 19 to be greater than the p_2 pressure for control position 15 by an amount proportional to the change in distance. That is, as the p_2 pressure for control position 19 increases, the p_2 pressure for control position 15 will decrease. The change in the p_2 pressures will cause the flow rates through pickoff control passages 35 to change in proportion to the deviation of rotor 7 from an original rotor axis position and adapt the signals from control passages 35 to be used as opposing controls for controlling fluid amplifiers 39 and 41.

Also in operation, the p_1 pressure is chosen so as to be generally 10 to 20 times higher than the p_2 pressure, which makes the orifices or throttles 29 very effective for not causing any variations in pressure p_1 or variations of flows through the orifices that might affect the p_1 pressure.

This particular pneumatic design offers a completely coerciveless pickup and allows for the first time a true flow sensor to pneumatic amplifiers. Pneumatic amplifiers have always required flow rates rather than pressure, and with this concept and design, large flow rates can be achieved by simple manipulation of the orifices or throttles.

It is to be understood that the form of my invention, herewith shown and described, is to be taken as a preferred example only, and that various changes in the size, shape and arrangement of parts may be resorted to, without departing from the spirit of my invention or the scope of the subjoined claims.

I claim:

1. A two degree of freedom pneumatic gyro including: a rotor member; a stator member; air bearing means between mating surfaces of said rotor and stator members and supporting said rotor member for rotation relative to said stator member; and pneumatic pickoff control

means disposed relative to said rotor and stator members and connected to fluid amplifier means for control thereof, said pneumatic pickoff control means including means in said stator member mating surface and coacting with means on said rotor member mating surface to establish flow rates to said fluid amplifier means that are proportional to the movement of said rotor member from a predetermined position, and means in said rotor member for exhausting fluid from said means on said stator member mating surface.

2. A two degree of freedom pneumatic gyro as set forth in claim 1, wherein said rotor and stator member have mating spherical surfaces.

3. A two degree of freedom pneumatic gyro as set forth in claim 1, wherein said air bearing means includes two latitude bands of support holds on the stator member.

4. A two degree of freedom pneumatic gyro including: a rotor member; a stator member; air bearing means supporting said rotor member for rotation relative to said stator member; and pneumatic pickoff control means disposed relative to said rotor and stator members and connected to fluid amplifier means for control thereof, said pickoff control means including four control positions located 90° apart around the periphery of the stator member, and the rotor member having an inner circumferentially tapered ramp surface and exhaust slots extending radially from said ramp surface.

5. A two degree of freedom pneumatic gyro as set forth in claim 1, wherein said air bearing means and said pneumatic pickoff control means are supplied pneumatic control fluid from different sources.

6. A two degree of freedom pneumatic gyro including: a rotor member; a stator member; air bearing means supporting said rotor member for rotation relative to said stator member; and pneumatic pickoff control means disposed relative to said rotor and stator members and connected to fluid amplifier means for control thereof, said rotor and stator members having mating spherical surfaces, said air bearing means including two latitude bands

5 of support holds on the stator member, said pickoff control means including four control positions located 90° apart around the periphery of the stator member, and the rotor member having an inner circumferentially tapered ramp surface and exhaust slots for exhausting fluid away from said ramp surface.

10 7. A two degree of freedom pneumatic gyro as set forth in claim 6, wherein said stator member is mounted in a casing that surrounds the rotor and stator members, and said casing having an exhaust opening therethrough.

15 8. A pneumatically operated gyro including: a stator member; a rotor member rotatably mounted relative to said stator member, said rotor and stator members having mating spherical surfaces; air bearing means supporting said rotor member relative to said stator member, said air bearing means including latitude bands of support holds on said stator member; pneumatic means for driving said rotor member relative to said stator member; and pneumatic pickoff means mounted relative to said 20 mating spherical surfaces of said rotor and stator members and connected to at least one fluid amplifier for control thereof to thereby adapt said amplifier for actuating control means in one degree of freedom, said pneumatic pickoff means including two control positions located 180° apart around the periphery of the stator member and an inner circumferentially tapered ramp surface on the rotor member and directly in front of said control 25 positions.
